UNITED STATES PATENT OFFICE.

EDWARD HILKER, OF CHICAGO, ILLINOIS.

MOP AND WRINGER THEREFOR.

SPECIFICATION forming part of Letters Patent No. 699,953, dated May 13, 1902.

Application filed August 26, 1901. Serial No. 73,339. (No model.)

To all whom it may concern:

Be it known that I, EDWARD HILKER, a citizen of the United States, residing at Chicago, in the county of Cook and State of Illinois, 5 have invented certain new and useful Improvements in Mops and Wringers Therefor, of which the following is a specification.

This invention relates to improvements in a mop and wringer therefor; and it consists 10 in certain peculiarities of the construction, novel arrangement, and operation of the various parts thereof, as will be hereinafter more fully set forth and specifically claimed.

The objects of my invention are to provide 15 a combined mop and wringer which shall be so constructed that the mop-cloth may be twisted or wrung so as to extract the water therefrom without soiling the hands of the operator and in which the crank used for 20 twisting or wringing the cloth may be operated with either hand of the operator.

Another object of the invention is to retain the cloth when it is being used as a mop directly under the block or body, so as to prevent 25 it slipping to one side thereof.

Still another object of the invention is to provide means for guiding the sleeve which carries the crank-handle on the mop-handle, so as to prevent said crank turning thereon 30 when not desired.

Other objects and advantages of the device will be set forth in the subjoined description and explanation.

In order to enable others skilled in the art 35 to which my invention pertains to make and use the same, I will now proceed to describe it, referring to the accompanying drawings, in which—

Figure 1 is a view in side elevation of a mop 40 and wringer therefor embodying my invention, showing the mop-handle shortened for the convenience of illustration and illustrating by dotted lines the position of the parts when in position for the mop-cloth to be wrung 45 or twisted. Fig. 2 is a plan view of the block or body and a portion of the handle with the mop-cloth removed. Fig. 3 is a view in end elevation of the sleeve and gear used for adjusting the mop-cloth and for wringing the 50 same, and Fig. 4 is a detached view of a hook or holder for one end of the mop-cloth.

Similar letters refer to like parts throughout the different views of the drawings.

A represents the body or mop-holder, which in the present instance is shown as being a 55 rectangular-shaped block of wood, but which may be of any other suitable material. This body is formed with an open-ended slot a, which provides prongs a', thus furnishing a bifurcated block or body. Between the 60 prongs a' and about the middle of the body is pivotally secured one end of the mop-handle B, which has extending longitudinally thereon a wire or rib b to act as a guide for the sleeve F, which comprises a cylindrical 65 portion G, which surrounds the mop-handle and has in its upper portion a slot g to receive and engage a pin or projection g' on the handle. As is clearly shown in the drawings, the slot g extends longitudinally in the cylindrical part G and then transversely and terminates in a recess, so that the pin g' may readily enter the slot, when by turning the sleeve F it will fit in the recess thereof and hold said sleeve in its raised position, as shown by 70 dotted lines in Fig. 1 of the drawings. Extending from the cylindrical portion G is a bracket g², which has on its free portion a cylindrical part h, in which is journaled the shaft h' of the hook or holder H, used for one 80 end of the mop-cloth I, which is preferably made in the form of a hank or loop. Near its upper end the cylindrical portion G of the sleeve F is provided on one of its sides with two lugs g³, through suitable openings in 85 which passes the crank-shaft G', which is provided at its end with a handle or knob g⁴ to be used for operating the gears employed for twisting the mop-cloth. Fixed on the upper end of the shaft h' of the hook or holder 90 H is a beveled gear L, which meshes with a similarly-shaped gear M, which is fixed on the end of the crank-shaft G', as is clearly shown in Fig. 3 of the drawings. Each of these gears is provided on its outer surface 95 near the central opening therein with lugs m, which are located a slight distance apart, so as to receive therebetween the bent portions m' and m² of the shafts h' and G', respectively, thus affording a convenient means for fixing 100 said gears on said shafts. The cylindrical portion G of the sleeve is provided with a

longitudinal groove g^5 on its inner surface for the reception and operation of the pin g' and the rib b on the mop-handle, and also for the purpose of allowing the sleeve to pass over the pin g' when it is desired to remove the sleeve from said handle.

While I have shown the gears L and M provided with lugs m to receive the bent ends of the shafts h' and G' and have found this construction to be a convenient one for fixing the gears on the shafts, yet I do not desire to be limited to said means, as I may secure them on the shafts in any other suitable manner.

15 Secured to the body or mop-holder A, and usually at its sides, is a bail E, which is preferably made of wire and has its outer ends e overlapping each other and bent inwardly toward the end of the body, as is clearly shown in Fig. 2 of the drawings. This bail may be made of one piece, as shown in said figure, in which case it may be employed to form the axis for the mop-handle. The mop-cloth I is secured at one of its ends to the transverse portion of the bail E and at its other end to the hook H, the inturned portion i of which will prevent said end being accidentally disengaged therefrom. When the mop-cloth is in the form of a hank or loop, it may be secured on the bail E by passing it between the ends e thereof, when said end will pierce the middle portion of the cloth and hold it in such a manner as to be evenly distributed under the body or block. 35 To use the mop for wiping or scrubbing, it is only necessary to slightly raise the sleeve F until the pin g' is freed from the recess in the slot g , when by turning the sleeve F in the proper direction the pin will pass out of the slot and allow the sleeve to slide down on the handle, where it may be stopped by a suitable projection r, in which operation the block or body A may be swung on the pivot of the mop-handle B, so that the mop-cloth 45 will lie under the body, as shown in Fig. 1 of the drawings. When it is desired to wring the water from the mop-cloth, the sleeve is raised on the mop-handle to the position shown by dotted lines in Fig. 1, when by turning the crank-shaft the said cloth will be

twisted and the water extracted therefrom, as is apparent.

Having thus fully described my invention, what I claim as new, and desire to secure by Letters Patent, is—

1. The combination of a bifurcated body, with a handle pivotally secured thereto, a bail secured on the body and extending crosswise one of its ends, a sleeve movably located on the handle and having means to fix it thereto, a rod or shaft journaled on said sleeve, a mop secured at one of its ends to said rod or shaft and at its other end to the said bail, and means to rotate the shaft, substantially as described.

2. The combination with a bifurcated body, of a handle pivotally connected thereto between its prongs, a bail secured on the body and extending crosswise one end thereof, a rib secured longitudinally on said handle, a sleeve movably secured on the handle and having means to fix it thereto, a shaft journaled on said sleeve, a mop secured at one of its ends to said shaft and at its other end to the bail, and means to rotate the shaft, substantially as described.

3. The combination of a bifurcated body, with a handle pivotally connected thereto between its prongs, a mop connected to one end of said body, and means movably secured on the handle and connected to the other end of the mop to raise, lower and twist the same, substantially as described.

4. The combination with a bifurcated body, of a handle pivotally connected thereto between its prongs, a bail secured on the body and extending crosswise one end thereof, a sleeve movable longitudinally on the handle, a shaft journaled on said sleeve, a beveled gear on said shaft, a mop connected at one of its ends to said shaft and at its other end to the bail, a crank-shaft journaled on the sleeve at right angles to the first-named shaft, and a beveled gear on the crank-shaft, substantially as described.

EDWARD HILKER.
